UNITED STATES PATENT OFFICE.

WILLIAM J. SHERMAN, OF ST. AUGUSTINE, FLORIDA.

EARTH-AUGER.

SPECIFICATION forming part of Letters Patent No. 250,293, dated November 29, 1881.

Application filed July 16, 1881. (No model.)

To all whom it may concern:

Be it known that I, WM. J. SHERMAN, a citizen of the United States, resident of St. Augustine, in the county of St. John's and State of Florida, have invented a new and valuable Improvement in Well-Boring Apparatus; and I do hereby declare that the following is a full, clear, and exact description of the construction and operation of the same, reference being had 5 to the annexed drawings, making a part of this specification, and to the letters and figures of reference marked thereon.

Figure 1 of the drawings is a representation of vertical longitudinal section of my invention. 15 Fig. 2 is a side view of the head-block. Fig. 3 is a cross-section on line $x-x$, Fig. 1; and Fig. 4 is a cross-section of one of the augers.

This invention relates to improvements in devices for boring wells; and it consists in the 20 construction and novel arrangement of parts, as hereinafter set forth.

In the annexed drawings, the letter a designates a block or head-piece having the tang a' for attachment to the operating mechanism, and a 25 flattened socket, a^2 , through which are made transversely the registering-slots b . Keyed to this head-piece in said socket are the auger-shanks c . These have at their upper ends the reduced ends or tangs, d , curved on the outer 30 side to fit the socket and flattened on their inner faces, e , in which faces are formed the angular grooves f . These shanks are held in the

socket by a gib, g , and cotter h passing through the slots b and the meeting notches or grooves f . The auger-shanks c are made inwardly concave in cross-section, and along the crowns of the curves run ribs k , which strengthen the shanks. At their lower ends these shanks have the reversely-projecting cutting-lips l . 35

Secured within one of the shanks, at its upper end, is a spring, m , the free end of which bears against the other shank. This spring tends to keep the shanks apart while working, sufficient room being provided in the socket a^2 to allow the necessary play. 40

The auger, as thus constructed and arranged, is secured by its tang a' to any suitable handle or to some operating mechanism. Power is applied so as to give a rotary movement to the auger when the cutting-lips l operate to 45 bore a hole in the earth.

Having described my invention, what I claim, and desire to secure by Letters Patent, is—

The combination of head-piece a , having socket a^2 , shanks c , having notched tangs d , 55 ribs k , and cutting-lips l , gib g , cotter h , and spring m , as set forth.

In testimony that I claim the above I have hereunto subscribed my name in the presence of two witnesses.

WILLIAM JOHN SHERMAN.
